UNITED STATES PATENT OFFICE.

THOMAS OWEN BATES, OF LIVERPOOL, ENGLAND.

MACHINERY FOR MAKING CUP-WAFERS, SUGAR-WAFER BISCUITS, AND THE LIKE.

No. 880,498.

Specification of Letters Patent.

Patented March 3, 1908.

Application filed November 20, 1906. Serial No. 344,229.

To all whom it may concern:

Be it known that I, THOMAS OWEN BATES, a subject of the King of England, residing at Liverpool, in the county of Lancaster, England, have invented new and useful Improvements in Machinery for Making Cup-Wafers, Sugar-Wafer Biscuits, and the Like, of which the following is a specification.

This invention has reference to machinery for making sugar cup wafers of various shapes sugar wafer biscuits, and the like of the kind in which the material is cooked between two plates hinged together and adapted to be moved in relation to each other about such hinge when charging the material to be cooked, and removing the cooked articles, and it has for its object to provide improvements hereinafter described, by which this type of article, and more especially cups, can be made expeditiously, economically, and of good quality and class.

The invention will be described with the aid of the accompanying drawings, which illustrate it; and the novel characteristics under it are set out in the claiming clauses concluding the specification.

In the drawings, Figure 1 is a side elevation in section, of the apparatus or machine constructed and adapted to make cup wafers and the like; Fig. 2 is a back end elevation; and Fig. 3 a plan; Fig. 4 is a detail view.

Referring to the drawings, according to this invention, the matrices 2 in which the cups are made, are provided on the plate 1; and this plate has hinged to it, at and by the hinge 9, a plate 10, of which 12 are the hinge cheeks fitting one on either side of the hinged boss 3 of the plate 1. The plate 10 contains the dies or inner formers 11, which form the cores to the articles being made.

The upper and lower plates 10 and 1 have at the front and back, projecting parts at 13, 13, which form trunnions, which rest in the front and back plates of the box or casing 17 of the machine; the edges of these plates being gapped out to receive the trunnions, and form bearings for same, upon which the whole device is adapted to revolve.

The whole of the movable parts, that is, the upper and lower plates 10, 1 are balanced by weighted levers 18, mounted on two hinge pins 19, mounted in bearings 20, the axes of which are normally coincident with the axis of the hinged pin of the hinge 9, connecting the upper and lower plates; and these levers

are connected to the front end of the plates by a bar 21 which is in the form of a fork at the back, the two ends of the fork being coupled up with the hinge pins 19 of the weighted levers 18; while the other part is 60 in the form of a bridge bar extending over the plates to the front portion, to which it is connected by a link 22, to one of the manipulating prongs, 14, of the upper plate 10; the lower prong 6 being coupled to the upper 65 prong 14 by a ring 7, which slips onto and off its end as and when desired. The link 22, at its lower end, is provided with an eye, which forms a bearing to the prong 14; and the link proper itself is disposed at one side of this eye, 70 as shown in Fig. 4.

When the two plates 1 and 10 are disconnected, which is effected by moving the ring 7 off the end of the prong 14, and the upper plate 10 is free to move upward upon the 75 hinge 9, it will be balanced by the weights 18, or moved up by them; and when in the upper position as shown in the dotted lines, the plate will be held up in such position by the weights thereby enabling the contents, that 80 is, the cups of biscuits, etc. to be moved from the matrices 2, and fresh batter supplied to them.

The lower prong 6 is hinged at 8 in the plate 1, at a point near its connection with the same, as shown; and has a short extension inwards of the hinge 8, by which means, when the two prongs are released from each other, by taking off the ring 7; and the lower one 6 is pressed down, the upper plate 10 will 90 be forced a slight distance up, and completely separated from the lower plate, thus obviating difficulties in dividing these plates which sometimes happens, due to the vacuum between them.

In connection with the plate 10 there is employed a plate 15 which separates the cups made from the cores or dies 11, by just removing them a sufficient degree to prevent their sticking to them on cooling, when 100 the door or upper plate 10 is opened. This plate 15 therefore acts as a stripping or starting means. The plate 15 is perforated, and the cores 11 pass through the holes in it, and it rests normally against the inner surface of the plate 10; the upper parts of the cores 11—which are made slightly larger than the widest part of such cores which act on the batter—practically fill the apertures; and the lower surface of this plate will act or 110

press upon the upper part of the batter, which generally spreads across the surface of the plate 1, and joins the cups together.

- The amount of movements of the stripper plate 15,—which is supported and its movement limited by the set screws 16—to effect this starting or stripping action, need be very small, and it need be only actuated from one end or part; and this is done, preferably, automatically, on the opening of the upper plate or lid 10, by a device connected with it, which, when the upper plate or lid is raised, acts on the stripper plate, and moves it away from such upper plate 10.
- 15 The device shown in the drawing for effecting this, is convenient and simple, and consists of a species of trigger or lever 23, hinged at 24 to the plate 10, having the front end lying over the stripper plate 15, and the other over a projection or cam-shaped device 4 on the end of the boss 3, which, when the plate 10 is moved up off the plate 1, and revolves about the hinge 9, will obstruct this trigger 23 and cause its front end to be depressed; 25 and this end being connected with pins 25 provided on the plate 15, will press it down, and away from the plate 10. Of course this action will be arranged to take place at the required moment.
- 30 The apparatus is heated by a burner 26 in the bottom of the box or base 10; and in the cooking operation the plate 1 and matrices 2 will be first downwards, so as to be heated by the burner, and then the whole device 35 turned round on the trunnions 5, by taking hold of and turning the prongs 14, 6, so that

the plate 10 becomes downmost, and will be heated by the burner. In this action, it will be seen that in turning it—the apparatus—so that the matrices 1 come upper most, the 40 prong 6 can lie above the prong 14, by reason of the link 22 being to one side of the vertical plane of same, as shown in Fig. 4.

What is claimed is:—

1. In machinery for making cup wafers, 45 sugar wafers, biscuits, and the like, two plates between which the material is cooked hinged together at one end, trunnions on which said plates revolve and a counter-balance weight lever having a hinge separate 50 from that of the plates, but coincident with that of the said plate hinge, and connected with the upper plate of the device; substantially as described.

2. In machinery for making cup wafers, 55 sugar wafers, biscuits, and the like, the arrangement of upper and lower plates 10 and 1, hinged together at one end; a weighted lever 21 hinged coincidently with the aforesaid hinge, and in the form of a bridge; and 60 projecting parts, as 14 and 16, adapted to be connected together, with one of which the end of the bridge bar 21 is connected; as herein set forth.

In testimony whereof I have signed my 65 name to this specification in the presence of two subscribing witnesses!

THOMAS OWEN BATES.
